US0D1020465S

(12) **United States Design Patent** (10) **Patent No.:** **US D1,020,465 S**
(45) **Date of Patent:** **** Apr. 2, 2024**

(54) **CONTAINER**

(71) Applicant: **Kraft Foods Group Brands LLC**,
Chicago, IL (US)

(72) Inventors: **David Joslyn**, Chicago, IL (US);
Rachel Drof, Northbrook, IL (US);
Lindsey Kubacki, Chicago, IL (US);
Scott Ora, McDonough, GA (US);
Jessica Soto, McDonough, GA (US);
Jonathan Dineen, McDonough, GA
(US); **Sahil Verma**, McDonough, GA
(US); **Dustin Wexler**, McDonough, GA
(US)

(73) Assignee: **Kraft Foods Group Brands LLC**,
Chicago, IL (US)

(**) Term: **15 Years**

(21) Appl. No.: **29/745,964**

(22) Filed: **Aug. 11, 2020**

(51) LOC (14) Cl. **09-01**

(52) U.S. Cl.

USPC **D9/529**; D9/574

(58) **Field of Classification Search**

USPC D9/563, 572, 573, 574, 575, 499, 549,

(57) **CLAIM**

The ornamental design for a container, as shown and
described.

DESCRIPTION

FIG. 1 is a top perspective view of a container according to
our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown illustrate features of the container
and form no part of the claimed design.

1 Claim, 7 Drawing Sheets
